[57] CLAIM

The ornamental design for high back chair-lounger with pull-out ottoman, as shown.

DESCRIPTION

FIG. 1 is a right-hand front perspective view, showing the high back chair-lounger with pull-out ottoman of my new design with the ottoman in the retracted position;

FIG. 2 is a front elevational view thereof;

FIG. 3 is a rear elevational view thereof;

FIG. 4 is a top view thereof;

FIG. 5 is a bottom view thereof;

FIG. 6 is a right view thereof;

FIG. 7 is a left view thereof;

FIG. 8 is a right-hand perspective view similar to FIG. 1, showing the high back chair-lounger with pull-out ottoman with the ottoman extended;

FIG. 9 is a top view of the design of FIG. 8;

FIG. 10 is a bottom view of the design of FIG. 8;

FIG. 11 is a right side view of the design of FIG. 8; and,

FIG. 12 is a left side view of the design of FIG. 8.
